CHARLES MARIE JULES PETIET, OF VILLENEUVE LA GARENNE, FRANCE,
ASSIGNOR TO SOCIÉTÉ ANONYME DES AUTOMOBILES ARIÉS, OF VILLENEUVE LA GARENNE, FRANCE.

STEERING MECHANISM FOR MOTOR-VEHICLES.

No. 816,935.

Specification of Letters Patent.

Patented April 3, 1906.

Application filed December 8, 1904. Serial No. 235,939.

To all whom it may concern:

Be it known that I, CHARLES MARIE JULES PETIET, a citizen of the Republic of France, residing in Villeneuve la Garenne, Seine, France, have invented certain new and useful Improvements in Steering Mechanism for Road Motor-Vehicles, of which the following is a specification.

The chief disadvantage of the various kinds of non-reversible steering mechanism at present employed in the majority of road motor-vehicles is that such mechanism is subjected to relatively rapid wear, owing to its construction, and that this wear is very difficult to take up, or at any rate a number of adjusting operations are required, and frequently the worn or imperfect parts have to be replaced or repaired.

The improved steering mechanism which forms the subject of the present invention has not been devised with the object of preventing the possibility of wear, but to permit of readily and perfectly taking up all wear or play which may occur by tightening up a single easily-accessible nut.

The improved steering mechanism is illustrated in vertical section in Figure 1. Fig. 2 is a plan of the rocking frame having two rollers mounted therein, for the purpose explained later.

The steering handle or tube A, turned by the driver, carries at its lower end an extension or part B, provided with right and left handed screw-threads *a* *b*. These latter may be arranged in different ways. The thread *a* may be inside the part B and the thread *b* outside, as in the drawings, or both threads may be on the outer or inner face of B and disposed one above the other. The advantage of the arrangement shown in the drawings, in which the threads are on the outer and inner faces of B, is simply that the mechanism is made shorter. In this particular case the two screw-threads engage, respectively, with a nut C and an internal screw D. Each of these two parts C and D has an abutment or extension, (lettered *c* and *d*, respectively.) These bear upon two rollers *e* *f*, carried by a small rocking frame or part E, which is rigidly connected to a shaft F, pivotally mounted in bearings and carrying at its extremity any usual or suitable means for

connecting it to the front wheels. The double-threaded extension B is secured in place in the present case by a large nut I, screwing onto the exterior of the casing G, a ball-bearing H being fitted between the nut and extension. The nut I can be secured rigidly in place after adjustment by means of a jam-nut J.

A reference to the drawings will at once show that whatever play may exist between the screws or between the abutments and the rollers by suitably tightening up the nut I the play may be taken up and all these parts held in good working contact, so as to cause them to bear in the direction in which the force is exerted.

What I claim, and desire to secure by Patent, is—

1. A steering mechanism including in combination a rocking shaft, a pair of members bearing on opposite sides of said shaft respectively, each of said members having a complete screw-thread, the thread of one being in the opposite direction to the thread of the other, a third member having two screw-threads corresponding respectively to the threads upon the first two members, for pressing said members alternately forward, and threaded means for taking up play by adjusting the third member toward the shaft.

2. A steering mechanism for automobiles including in combination a pair of members *c* and *d* respectively, a rocking frame *E*, rollers *e* and *f* carried at opposite sides of said frame, in the line of movement of said members but unconnected thereto, an internal left-handed screw *C* carrying said member *c* and an external right-handed screw *D* carrying said member *d*, an intermediate double screw *B* engaging said screws *C* and *D* and adapted when rotated to move said screws *C* and *D* in opposite directions, and a nut *I* securing said screw *B* in place and adjustable to take up play between the members *c* and *d* and the rollers *e* and *f*.

In witness whereof I have hereunto signed my name, this 24th day of November, 1904, in the presence of two subscribing witnesses.

CHARLES MARIE JULES PETIET.
